[57] CLAIM

The ornamental design for an accessory stand for use in shining boots and shoes, substantially as shown and described.

DESCRIPTION

FIG. 1 is a left side elevation view of an accessory stand for use in shining boots and shoes constructed in accordance with and embodying my new design.

FIG. 2 is a front elevational view thereof.

FIG. 3 is a right side elevation view of the new accessory, particularly showing the arrangement of parts including a foot member at the end of a leg for clampingly engaging a boot or shoe by pressure applied to a treadle while shining the boot or shoe.

FIG. 4 is a rear elevation view thereof.

FIG. 5 is a top plan view thereof.

FIG. 1

FIG. 2

FIG. 3

FIG. 4

FIG. 5
